(57) **CLAIM**

The ornamental design for an electronic toll collection machine, as shown and described.

DESCRIPTION

FIG. 1 is a front view of a front cover of electronic toll collection machine showing our new design;

FIG. 2 is a rear view thereof;

FIG. 3 is a top (plan) view thereof;

FIG. 4 is a bottom view thereof;

FIG. 5 is a right-side view thereof;

FIG. 6 is a left-side view thereof;

FIG. 7 is a perspective view of the front cover of electronic toll collection machine showing our new design;

FIG. 8 is a cross section view taken in the direction of line A—A of FIG. 1 with the internal mechanism omitted;

FIG. 9 is a cross section view taken in the direction of line B—B line of FIG. 3 with the internal mechanism omitted; and,

FIG. 10 is another perspective view thereof, with the card holder cover shown in an opened position.

The article according to the present design application relates to an on-vehicle electronic toll collection machine in which an IC card is mounted in a card holder, which machine enables drivers to make an automatic payment at a toll gate. According to the electronic toll collection machine of the present design application, a card holder cover which covers the upper surface of the card holder is slid in a transverse direction to open an IC card mounting portion so that the IC card can be mounted therein.
